UNITED STATES PATENT OFFICE.

NOBLE ECKLES, OF SAN DIEGO, CALIFORNIA, ASSIGNOR OF THREE-FOURTHS TO
LEWIS W. RHODE, OF SAN DIEGO, CALIFORNIA.

CARBURETOR.

Application filed April 22, 1920. Serial No. 375,691.

My invention relates to carburetors for preparing fuel for internal combustion engines and the objects of my invention are: first, to provide a carburetor which is so constructed that the fuel in proper regulated quantities may be drawn from a tank on a lower elevation by the vacuum created by the operation of the pistons in the cylinder of the engine thus dispensing with the conventional vacuum or pressure system of fuel supply as used in the conventional automobile, or the like; second, to provide a carburetor in which a continuous partial vacuum of varying degree is maintained in the fuel bowl at substantially all motor speeds and under substantially all conditions thus causing the fuel supply bowl to be replenished at substantially all times by the partial vacuum in said fuel supply bowl; third, to provide a carburetor of this class in which the operation of the carburetor and regulation of the proportionate quantities of fuel and air are entirely controlled by the relative degree of partial vacuum between the fuel supply bowl and the air supply passage which relative vacuum regulation is operated automatically with the operation of the throttle; fourth, to provide a carburetor of this class which is adjustable throughout; fifth, to provide separate means for regulating the vacuum in the carburetor for use at low speed and idling; and sixth, to provide a carburetor of this class which is very simple, economical of construction, durable, flexible, efficient in its action, easy to repair and install and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a longitudinal sectional view of my carburetor through the middle thereof; Fig. 2 is a sectional view through 2—2 of Fig. 1; Fig. 3 is a sectional view through 3—3 of Fig. 1; Fig. 4 is a top or plan view of a fragmentary portion of my carburetor

and Fig. 5 is a sectional view through 5—5 of Fig. 1.

Similar characters of reference refer to similar parts and portions throughout the several views of the drawings.

The main casing 1, fuel bowl 2, float 3, anterior air valve 4, spring 5, valve adjusting screw 6, intermediate regulating valve 7, throttle valve 8, drain conductor 9, low speed fuel feed 10, relative vacuum regulating valve 11, and fuel conductor 12 constitute the principal parts and portions of my carburetor. The main casing 1 is substantially a conducting tube functioning as an air conductor. It is provided with a dip portion forming a bowl 1^a surrounding the fuel inlet nozzle 1^c into said casing and provided with a downwardly extending web 1^b therein for guiding and deflecting the air downwardly past the fuel inlet nozzle 1^c. This casing portion 1 is provided with an inwardly projecting portion 1^d in the one side thereof which is provided with a narrow slot 1^e therein shown best in Fig. 3 and mounted over this projecting portion 1^d in said casing is an intermediate regulating valve 7 which is supported in the wall of said casing and provided with an extended portion 7^a extending out through the one side and mounted on this extending portion 7^a is an arm member 7^b for operating said valve 7, which is for the purpose of controlling or increasing the suction in the air passageway in the region of the nozzle 1^c and back-suction connection 11^c. The casing 1 is provided with an extended portion 1^f which serves as an air inlet to the carburetor. Mounted on the lower side of this portion 1^f is a spider member 1^g which is provided with a socket portion 1^h and around this socket portion through the spider members the air is adapted to pass into the carburetor. Mounted in this socket portion 1^h is a valve stem 4^a thus forming a support for the valve which functions to prevent its fluctuating or vibrating with the movement of the air into the carburetor. The valve seating portion of the valve 4 is provided with a thin edge which is adapted to move up and down over the slot 1^e as the air passes into the carburetor and the valve is actuated by the vacuum caused by the throttle of the carburetor. This valve is also provided with a spring 5 which en-

gages the inwardly extended end of the adjusting screw 6 which provides for adjusting the valve 4. Mounted around the cup portion 1^a of the casing 1 is the fuel bowl 2 sometimes termed the float chamber. Supported in a downwardly extended portion 1¹ of the casing 1 and mounted in this downwardly extended portion is a needle valve 1¹ which is adapted to regulate the flow of fuel 10 from said bowl through the inlet nozzle 1^c. Mounted in this bowl 2 is a float 3 which is pivotally mounted upon downwardly extended flange portions 1^k of the casing 1 and provided with the usual valve for regulating the flow of fuel to the bowl. This 15 valve engages an intake conductor 12 which extends to the fuel tank which may be in any position desired. Mounted in this casing 1 on the engine side of the fuel nozzle 1^c is the throttle 8 which is operated in the ordinary manner and communicating with the interior of the casing between the throttle valve and the intake manifold of the engine is a conductor 9^a which is provided 20 with a valve 9^b therein and communicating therewith is the conductor 9 which extends to the bottom of the bowl 1^a and is adapted to drain the bottom of this bowl 25 of surplus fuel therein caused by condensation with the varying openings of the throttle and the needle valve 9^b regulates the opening in said conductor 9. Communicating with this conductor 9^a is another conductor 10 which extends downwardly and 30 communicates with the lower side of the interior of the fuel bowl 2 and is for the purpose of providing fuel to the engine from the carburetor bowl in small quantities for low speed. Mounted on the side of the 35 carburetor is a conductor 11^a connecting the interior of the fuel bowl with the interior of the casing 1 and it is provided with a needle valve 11 for regulating the opening through said conductor. This valve and 40 conductor is for the purpose of regulating and tending toward equalizing the vacuum in the casing and float chamber when running at low speed.

Though I have shown and described a 50 particular construction, combination and arrangement of parts and portions and a certain method of controlling the relative vacua between the carbureting chamber and the constant level chamber I do not wish to be limited to this particular construction, combination and arrangement herein described but desire to include in the purview of my invention the construction, combination and arrangement substantially as set forth in 55 the appended claims.

It is obvious that with this construction there is provided a means for taking the fuel from a fuel tank although considerably below the carburetor and conducting it directly to the carburetor bowl and for mix-

ing this fuel with air in proper regulated quantities and conducting it to the cylinder of the engine; that no extra vacuum system or mechanism is required; that the carburetor is so constructed that the flow of fuel to the bowl is in proportion to the vacuum in the bowl which is regulated in the proper ratio with the air passing through the carburetor; that the relative variation in the vacuum existing in the main air passage and in the float chamber varies the amount of gasoline which passes through the spray nozzle 1^c; that the principle involved in this carburetor is one in which the action depends entirely upon the change in the relative vacuums between that maintained in the fuel supply bowl and that maintained in the main air supply passage of the carburetor and that as the throttle is opened the vacuum in the main casing is slightly increased thus opening the air valve and decreasing the vacuum maintained in the float chamber by means of the air valve exposing a part of the slot 1^e to the atmospheric pressure which in turn allows more gasoline to pass through the spray nozzle 1^c to be mixed with a larger volume of air passing through the main casing.

Having thus described my invention what I claim as new and desire to secure by Letters Patent is:

1. In a carburetor, the combination of a carbureting chamber having an air inlet and a mixture outlet, an anterior air valve controlling said air inlet, a throttle valve controlling said mixture outlet, a constant level fuel chamber, means adapted to transmit suction from said carbureting chamber to said constant level chamber, and a port mechanically controlled by the movement of said air valve and arranged to be alternately connected thereby to the atmosphere or to the suction of said carbureting chamber for controlling the admission of air to said constant level chamber.

2. In a carburetor, the combination of a carbureting chamber having an air inlet and a mixture outlet, an air valve controlling said air inlet, a constant level fuel chamber, a fuel inlet to said carbureting chamber fed from said constant level chamber and a port communicating with said constant level chamber and cooperating with said air valve, said port being arranged whereby the movement of said air valve differentially exposes varying areas of said port to the suction posterior to said air valve and to the atmosphere anterior to said air valve.

3. In a carburetor, the combination of an air passageway, an automatic air valve controlling the inlet to said air passageway, a throttle controlling the outlet, an intermediate valve between said air valve and said throttle, a fuel supply chamber, a fuel inlet fed from said fuel supply chamber and dis-

- charging into said air passageway, and a passageway communicating with said fuel chamber above the fuel level therein and having ports communicating with said air passageway between said automatic air valve and said intermediate valve, and between said intermediate valve and said throttle.
4. In a carburetor, the combination of an air passageway having an inlet and an outlet, an automatically operating air valve controlling said inlet, a throttle controlling said outlet, an intermediate valve, a constant level fuel supply chamber, a fuel inlet fed from said supply chamber and discharging into said air passageway at a point between said intermediate valve and said throttle, a passageway extending from said fuel supply chamber and opening into said air passageway between said automatic air valve and said intermediate valve, and a passageway extending from said supply chamber and opening into said air passageway between said intermediate valve and throttle.
5. In a carburetor, the combination of a carbureting chamber having an air inlet and a mixture outlet, an automatically operating air valve controlling said air inlet, a throttle controlling said outlet, a manually operated intermediate valve in said carbureting chamber between said air valve and said throttle, a constant level fuel supply chamber, a fuel nozzle drawing fuel from said supply chamber and discharging into said carbureting chamber between said intermediate valve and said throttle, a passageway communicating with said fuel supply chamber above the level therein and opening into said carbureting chamber through ports on opposite sides of said intermediate valve, and means for varying the suction communicated through said passageway.
6. In a carburetor, the combination of a carbureting chamber having an air inlet and a mixture outlet, a fuel supply chamber, a fuel inlet from said fuel supply chamber to said carbureting chamber, a throttle valve controlling the mixture outlet, an air valve for controlling the air inlet, a passageway from said fuel supply chamber to said carbureting chamber, an intermediate valve in said carbureting chamber positioned to control the effect of the suction in said carbureting chamber on said passageway, said air valve being adapted in its opening movement to move along the entrance of said passageway to act as a valve for said passageway to differentially proportion the suction effect in said passageway and airflow thereto when said intermediate valve is open.
7. In a carburetor, the combination of a carbureting chamber having an air inlet and a mixture outlet, a fuel supply chamber, a fuel inlet from said supply chamber to said carbureting chamber, a throttle valve controlling said mixture outlet, an automatic valve controlling the air inlet, a passageway extending from said carbureting chamber to said fuel supply chamber above the level of fuel therein, an intermediate valve in said carbureting chamber operable to control the effect of the suction in said carbureting chamber on said passageway and said automatic valve, said intermediate valve when closed disconnecting said passageway and said automatic valve from the suction effect in said carbureting chamber and when open exposing said passageway and said automatic valve to the suction effect whereby said automatic valve will be operated, said automatic valve when in operation cooperating with said passageway to differentially expose said passageway to the suction effect and to air flow.

In testimony whereof, I have hereunto set my hand at San Diego, California, this 16th day of April, 1920.

NOBLE ECKLES.
